UNITED STATES PATENT OFFICE.

JOHN B. GRANT, OF ATLANTA, GEORGIA.

BILL-BOARD.

977,862.

Specification of Letters Patent. Patented Dec. 6, 1910.

Application filed March 31, 1910. Serial No. 552,647.

To all whom it may concern:

Be it known that I, JOHN BAIN GRANT, a citizen of the United States, residing at Atlanta, in the county of Fulton and State 5 of Georgia, have invented a new and useful Bill-Board, of which the following is a specification.

This invention relates to bill boards and the like.

10 The principal object of the invention is to provide a device of the character specified which is adapted to be easily and quickly placed in position upon a lot or other piece of ground no matter how uneven the surface 15 may be, and which can be properly trued or leveled without regard to the unevenness of the surface of the ground.

A further object of the invention is to provide a device of the character specified 23 which can be assembled either in the form of a single or double deck bill board, the upper line of the board being disposed slightly in rear of the lower line thereof.

25 With the foregoing and other objects in view which will appear as the description proceeds, the invention resides in the combination and arrangement of parts and in the details of construction hereinafter described and claimed, it being understood 30 that changes in the precise embodiment of invention herein disclosed can be made within the scope of the claims without departing from the spirit of the invention.

35 In the accompanying drawing forming part of this specification:—Figure 1 is a perspective view of a bill board constructed in accordance with the present invention, the view being taken from the rear of the board. Fig. 2 is a side elevation of a bill 40 board arranged in accordance with the invention in double deck form.

Like reference numerals indicate corresponding parts in the different figures of the drawing.

45 The reference numeral 1 indicates the bill board which may be of any suitable form and construction, and which, in the embodiment of invention illustrated, is formed of sheet metal or the like having its upper edge bent forward in the form of a flange 2 having a downwardly curled forward edge 3 which is adapted to serve as a protector for the bills on the board 1, the flange 2 and edge 3 serving to deflect rain or moisture. 50 Extending longitudinally along the rear surface of the board 1 are bracing members 55

or bars 4 which are secured to the board in any suitable manner such as by means of the bolts 5. The uppermost brace member 4 preferably is disposed a short distance below the upper edge of the board 1 as shown. Secured to the brace members 4 in any suitable manner such as by means of the bolts 6, are a number of vertically extending supports or bars 7. The supports or bars 7 preferably although not essentially are circular in cross section. The supports 7 at their lower ends extend some distance below the lowermost bracing member 4 as well as the lower edge of the board 1, and at their upper ends the supports 7 preferably extend approximately to the upper edge of the bill board, which causes their upper ends to be some distance above the upper edge of the uppermost bracing bar 4 as shown. The supports 7 at their lower ends are adjustably fitted into the interior of the tubular ground members or devices 9, said tubular members being closed and pointed at their lower ends as indicated at 10 and being provided with adjusting 80 screws or other suitable locking devices 11 which can be screwed in so as to engage the outer surfaces of the supporting members 7 and hold them in any position within the tubular members 9 to which they may have 85 been adjusted.

In erecting the bill board the ground devices or tubular members 9 are driven into the soil and the supports 7 of the bill board are fitted thereinto, the different members 7 90 being differently adjusted in the ground members 9 so as to compensate for any irregularities in the surface of the land. In this manner the board 1 can always be disposed in a true horizontal position no matter 95 how irregular the surface upon which it is erected may be.

The means for bracing the board 1 preferably consists of a plurality of brace bars 15 each of which is pivotally and detachably connected with one of the supports 7 at its upper end as indicated at 16 and at its lower end is flattened as indicated at 17 and is formed with a plurality of perforations or openings 18 each adapted to receive a bolt 105 19 which extends through a ground member 20 having in its upper end a slot 21 of a thickness sufficient to receive the flattened portion 17 of the brace member 15. By arranging the bolts 19 of the different ground members 20 in different holes 18 of the brace members 15, said brace members can be ad-

justed so as to accommodate irregularities of the soil in which the ground members 20 are embedded.

When it is desired to arrange the improved bill board of the present invention in a plurality of tiers, the arrangement illustrated in Fig. 2 of the drawing is employed. In this construction the two bill boards 1-1 are of the same construction approximately 10 as that shown in Fig. 1. Connecting members 25 are employed for connecting the upper ends of the lower tier with the lower ends of the upper tier as shown. Each of these connecting members 25 is formed preferably at its forward end with an elbow 26 having a downward extension which is adapted to telescope over the upper end of the support 7 above the upper brace member 4 so as to secure a firm grip thereon. At its 20 rear end each of the connecting members 25 is provided with a vertically extending tubular portion 27 which forms a T-joint adapted to receive the lower end of the standard 7 of the upper tier of the bill 25 board. The portions of the supports 7 which project below the tubular member 27 of each connecting piece 25 as shown in Fig. 2, are adjustably fitted into the upper end of the ground members 9' which are the same as 30 those shown in Fig. 1 except that they are longer so as to provide a greater height above the surface of the ground, the members 9' being provided with the adjusting screws 11' the same as in the other form of 35 the invention. In this modified construction, the brace members 15 are exactly the same as those shown in Fig. 1 except that they are longer. The brace members 15 are pivotally and detachably connected at 40 with the support 7 of the upper bill board and at their lower end are adjustably connected with the ground members 20 the same as in Fig. 1.

From the foregoing description taken in 45 connection with the drawing, it will be seen that the device of the present invention is strong, simple, durable and inexpensive in construction as well as thoroughly practical in use. It is adapted to be easily and quickly 50 erected upon the surface soil of irregular

nature as easily as upon level ground. Moreover it is adapted to be arranged in one or two tiers without changing or altering the construction of the bill board in the slightest degree, it being merely necessary to use the 55 additional set of ground devices 9' and slightly longer bracing members 15.

What is claimed as new is:—

1. A bill board having longitudinally extending bracing members on the rear face 60 thereof, vertically extending supports connected with said bracing members, said supports extending above the bracing members at their upper ends and below the bracing members at their lower ends, ground devices 65 having sockets to receive the lower ends of said supports and provided with means for locking said supports in different positions of adjustment in said sockets, bracing bars pivotally and detachably connected with 70 said supports adjacent their upper ends, and ground members having slotted upper ends to receive the lower ends of said bracing members, said slotted upper ends being adjustably connected with the lower ends of 75 said bracing members.

2. The combination of a pair of bill boards each having longitudinally extending braces thereon, supports connected with 80 said braces and extending at their upper ends above the same and at their lower ends below the same, ground devices adjustably connected with the lower ends of the supports of each of said bill boards, connecting members connected at their forward ends 85 with the upper ends of the supports of one of said bill boards and at their rear ends with the lower ends of the supports of the other bill board, and braces connected with the upper portion of the upper bill board 90 and having ground members adjustably connected therewith.

In testimony that I claim the foregoing as my own, I have hereto affixed my signature in the presence of two witnesses.

J. B. GRANT.
